No. 882,966.

PATENTED MAR. 24, 1908.

H. C. REYNOLDS.

TROLLEY.

APPLICATION FILED AUG. 24, 1907.

UNITED STATES PATENT OFFICE.

HENRY C. REYNOLDS, OF PORTERSVILLE, CALIFORNIA, ASSIGNOR OF ONE-HALF TO ALBERT J. DE LANEY, OF PORTERSVILLE, CALIFORNIA.

TROLLEY.

No. 882,966.

Specification of Letters Patent. Patented March 24, 1908.

Application filed August 24, 1907. Serial No. 389,969.

To all whom it may concern:

Be it known that I, HENRY C. REYNOLDS, a citizen of the United States, and a resident of Portersville, in the county of Tulare and State of California, have invented a new and useful Improvement in Trolleys, of which the following is a full, clear, and exact description.

The purpose of the invention is to provide a simple, economic and reliable construction of trolley pole and head adapted especially for overhead work, and which will be self-adjustable since the two said parts will automatically so adjust themselves that the trolley head will stand almost horizontal on curves and overhead switches.

It is also a purpose of the invention to provide a pivotal connection between the head and the pole, wherein the head can turn laterally and freely to a predetermined angle to the pole, and yet have limited vertical movement when necessary without in any manner interfering with the said lateral movement, since one member of the connecting mechanism will not at any time unduly bind the other member within the prescribed limitation of movement.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a side elevation of the upper part of a car and a side elevation of the improved trolley head and pole applied; Fig. 2 is an enlarged side elevation of the trolley head and the end of the pole coupled thereto; Fig. 3 is a plan view of the parts shown in Fig. 2; Fig. 4 is an enlarged longitudinal section through the trolley head and a plan view of the entering end of the trolley pole and illustrates the position of the parts when the head is at its greatest angle with reference to the pole; and Fig. 5 is a perspective view of the end of the trolley pole.

A represents the side of a trolley car, B the trolley pole applied thereto, and C the trolley head. The trolley head is constructed with two forward vertical opposing cheek pieces 10 and 11, and between these cheek pieces 10 and 11 the trolley wheel 12 is mounted to

turn freely upon a fixed pin 13 or equivalent means of support. At the rear of the central portion of the body of the said trolley head two horizontal arms 14 and 15 are located, an upper and a lower arm, as is best shown in Fig. 2, and the space between these upper and lower arms 14 and 15 connects with a chamber 16, which chamber extends through the side portions of the said body, and in this chamber 16 a pinion 17 is vertically located, the said pinion being of the elongated type, and its end portions 18, which constitute trunnions, are preferably beveled, as is particularly illustrated in Fig. 2, and the said trunnions of the pinion 17 are suitably mounted in the aforesaid upper and lower arms 14 and 15.

At the outer end of the trolley pole B, or that portion of the pole which enters the space between the aforesaid upper and lower arms 14 and 15, a segmental head 19 is formed, which lies horizontally in the said space between the aforesaid arms 14 and 15, as is best shown in Fig. 4. The convexed or outer surface of the said head 19 is provided with teeth 20, for engagement with the teeth on the pinion 17, and the said teeth 20 are beveled, inclining usually from the top downward, as is illustrated in Fig. 2, and likewise in Fig. 5. The toothed surface 20 of the head 19 is eccentric with a pivot pin 21 that serves to pivot the trolley pole B to the head C, as is clearly illustrated in Fig. 4, and the inner faces of the upper and lower arms 14 and 15 are beveled in opposite directions from a point near their centers in an outward direction to the aforesaid chamber 16, in which the pinion 17 is mounted to turn, therefore a substantially triangular space is provided between the upper and lower faces of the head 19 of the trolley pole and the inner faces of the arms 14 and 15, as is clearly illustrated in Fig. 2. This space 22 just referred to admits of the head having a vertical movement to a limited extent relatively to the head, when occasion shall so require, without in any manner unduly jamming the teeth 20 of the trolley pole head on the teeth of the pinion 17; thus also permitting the head to freely turn laterally relatively to the trolley pole B under all conditions.

The formation of the toothed surface 20 of the head 19 is such that while at a point about centrally between the ends of said toothed surface there is comparative freedom of

touch between the teeth of the head 19 and the teeth of the pinion, but as the outermost teeth are reached the contact becomes more pronounced, until when the extreme outer 5 teeth have been reached at either end of the said head, the engagement between the head and the pinion will be such as to prevent the head from turning further in that direction.

This device is exceedingly simple and is 10 reliable in operation, and it is evident that the head C can remain horizontal when turning a curve or passing a switch, and that the trolley head can accommodate itself automatically to any curve no matter how pronounced. 15

Having thus described my invention, I claim as new and desire to secure by Letters Patent,—

1. In a trolley, a trolley head, a pinion 20 mounted thereon, a trolley pole mounted in the head, a toothed segment carried by the pole, which segment is in mesh with said pinion, the movement of the segment relatively to the pinion being limited in both 25 directions by the formation of the toothed surface of the segment.

2. In a trolley, a trolley head, a pole on which the head is pivoted, a pinion mounted

in the head, and a segmental gear in mesh with the pinion and constituting a head for 30 the entering end of the pole.

3. In a trolley, a trolley head, a pole on which the head is pivoted for lateral movement, a pinion mounted in the trolley head, and a segmental gear at the entering end of 35 the trolley pole, the teeth whereof mesh with the said pinion and are eccentric to the pivot for the pole.

4. In a trolley, a trolley head, a pole on which the said head is mounted for lateral 40 and for vertical movement, a pinion mounted in the trolley head, and a segmental gear at the entering end of the trolley pole, the teeth whereof mesh with the said pinion and are eccentric to the pivot of the pole, the 45 toothed surface of the said gear being also given a downward and inward inclination from the upper portion of the gear.

In testimony whereof I have signed my name to this specification in the presence of 50 two subscribing witnesses.

HENRY C. REYNOLDS.
